CLAIM

The ornamental design for a container, as shown and described.

DESCRIPTION

FIG. 1 is a perspective view of a container, such as for storing magazines or other periodicals, embodying one aspect of our new design;

FIG. 2 is a front elevational view of the container of FIG. 1;

FIG. 3 is a rear elevational view of the container of FIG. 1;

FIG. 4 is a right side profile view of the container of FIG. 1;

FIG. 5 is a left side profile view of the container of FIG. 1;

FIG. 6 is a top plan view of the container of FIG. 1;

FIG. 7 is a bottom plan view of the container of FIG. 1;

FIG. 8 is a perspective view of a container, such as for storing magazines or other periodicals, embodying another aspect of our new design;

FIG. 9 is a front elevational view of the container of FIG. 8;

FIG. 10 is a rear elevational view of the container of FIG. 8;

FIG. 11 is a right side profile view of the container of FIG. 8;

FIG. 12 is a left side profile view of the container of FIG. 8;

FIG. 13 is a top plan view of the container of FIG. 8;

FIG. 14 is a bottom plan view of the container of FIG. 8;

FIG. 15 is a perspective view of a container, such as for storing magazines or other periodicals, embodying another aspect of our new design;

FIG. 16 is a front elevational view of the container of FIG. 15;

FIG. 17 is a rear elevational view of the container of FIG. 15;

FIG. 18 is a right side profile view of the container of FIG. 15;

FIG. 19 is a left side profile view of the container of FIG. 15;

FIG. 20 is a top plan view of the container of FIG. 15; and,

FIG. 21 is a bottom plan view of the container of FIG. 15.

The subject matter shown in broken lines form no part of the claimed design.
